UNITED STATES PATENT OFFICE.

WILLIAM BLACK, OF RICES LANDING, PENNSYLVANIA.

CAGE FOR MINE AND ELEVATOR SHAFTS.

No. 809,899.

Specification of Letters Patent.

Patented Jan. 9, 1906.

Application filed February 6, 1905. Serial No. 244,451.

To all whom it may concern:

Be it known that I, WILLIAM BLACK, a citizen of the United States of America, residing at Rices Landing, in the county of Greene and State of Pennsylvania, have invented 5 certain new and useful Improvements in Cages for Mine and Elevator Shafts, of which the following is a specification, reference being had therein to the accompanying drawings.

This invention relates to certain new and useful improvements in cages for mine and elevator shafts, and more particularly to that type of cage which is employed for conveying 10 cars.

The invention has for its object to provide 15 a novel form of cage entirely constructed of metal.

The cage as constructed by me is particularly adapted for mine-shafts for conveying mine-cars from the different rooms of the mine to the top of the shaft, and I have provided novel means whereby the long timbers and girders which are used in mines for props 20 can be readily hauled upon my improved cage.

With the above and other objects in view the invention finally consists in the novel construction, combination, and arrangement 25 of parts, which will be hereinafter more fully described and then specifically pointed out in the claims, and, referring to the drawings accompanying this application, like numerals of reference designate corresponding parts 30 throughout the several views, in which—

Figure 1 is a side elevation of my improved cage. Fig. 2 is a top plan view thereof partly broken away. Fig. 3 is a front view of my improved elevator-cage.

To put my invention into practice, I have 35 constructed my improved cage of structural steel and iron, and some parts of the cage are formed of standard material, while other parts are formed of special castings. The base of the cage consists of two sills 11, which are secured together by a plurality of transverse braces 2. These braces are formed of sections of pipe cut the desired length and threaded upon each end, whereby they may 40 be interposed between the sills 11. The floor of the cage is formed of a plurality of substantially channel-shaped plates 3, the depending flanges 4 of which are pierced to permit of the braces 2 extending therethrough. 45 Mounted between said plates upon the braces

2 are tracks 4' 4', upon which travels the car to be hoisted.

The reference-numerals 5 5 indicate the main frames or bolsters of my improved cage, and these frames are adapted to be connected to the sills 11 by a plurality of vertically-arranged braces 6, which are similar in construction to the braces 2, heretofore described. The frames 5 5 are provided with transverse braces 7 7, to which are hinged, as indicated at 8 8, plates 9 9, these plates forming the top or roof of my improved cage. The frames 5 5 are provided with horizontally-aligned openings 10 10. Supported by the transverse braces 7 7 and the casing 11 are two top plates 35 35, which, together with the plates 9 9, form the roof or top of the cage.

It will be observed that I have constructed my improved mine-cage entirely of metal, and the use of bolts and nuts is dispensed with, whereby it will not be possible for any part of the cage to become disconnected and cause an accident.

Comparatively few parts are used in the construction of my improved cage, and I do not care to confine myself to the use of sections of pipes or tubing for braces, as tie-rods can be conveniently used in place of the tubing.

What I claim, and desire to secure by Letters Patent, is—

1. A cage of the type described comprising sills, flooring supported by said sills, said flooring consisting of channel-shaped plates and braces extending through the depending edges of said plates, through said sills a track supported on said flooring, bolsters from which the sills are supported and vertical and oblique braces connecting said bolsters with said sills.

2. A cage of the type described, consisting of parallel sills, transverse braces securing said sills together, a floor composed of channel-shaped plates, said braces extending through said plates, tracks mounted on said floor, bolsters arranged above the sills, vertical braces connecting said bolsters to said sills, transverse braces connecting said bolsters together, and plates hinged to said last-named transverse braces and constituting the roof of the cage.

3. A cage of the type described, comprising metallic sills, transverse braces connecting said sills, a metallic flooring mounted on said braces, metallic bolsters, vertical braces, an-

gularly-disposed braces connecting said sills with said bolsters, transverse braces connecting said bolsters together and plates hinged to said last-named braces and constituting the top of the cage.

4. The combination in an elevator-cage of sills, channel-shaped plates arranged between said sills having depending flanges, braces extending between and passing through the sills and passing through the depending

flanges of said channel-plates, and tracks arranged between said channel-plates, said braces extending through said tracks.

In testimony whereof I affix my signature in the presence of two witnesses.

WILLIAM BLACK.
